UNITED STATES PATENT OFFICE.

JOHN BEYSTRUM, OF PITTSBURG, PENNSYLVANIA.

ROTARY ENGINE.

SPECIFICATION forming part of Letters Patent No. 358,374, dated February 22, 1887.

Application filed August 6, 1886. Serial No. 210,185. (No model.)

To all whom it may concern:

Be it known that I, JOHN BEYSTRUM, of Pittsburgh, in the county of Allegheny and State of Pennsylvania, have invented a new 5 and useful Improvement in Rotary Engines; and I do hereby declare the following to be a full, clear, and exact description thereof.

My invention relates to rotary steam-engines, its principal objects being to provide a simple 10 and positive means of operating the pistons within the engine-cylinder and rotary head, to confine the steam within the steam-chamber and pack the chamber, to guide, support, and pack the pistons in their movement within 15 the cylinder and rotary head, and to lubricate the bearings of the piston-journals.

My invention consists, essentially, in combining with the engine-cylinder a rotary piston-head secured concentrically upon the 20 power-shaft and eccentrically within the cylinder, a stationary pin extending through the cylinder-head and extending into the space within the piston-head, arms or pitmen journaled on said pin, and sliding pistons pivoted 25 at the outer ends of the pitmen and sliding through the piston-head, the pitmen acting to hold the pistons in contact with the interior wall of the cylinder as the piston-head rotates therein.

It also consists in means for lubricating the 30 journals of the pitmen through the stationary pin on which they are mounted.

It also consists in certain other improvements in the construction of the engine and 35 the parts thereof.

To enable others skilled in the art to make and use my invention, I will describe the same more fully, referring to the accompanying drawings, in which—

Figure 1 is a vertical central section of my 40 improved rotary engine. Fig. 2 is a plan view, partly in section, of the bed-plate. Fig. 3 is an end view, the cylinder-head and side disk being removed, and the lower half being 45 shown in section. Fig. 4 is a perspective view of the pistons removed from the head. Fig. 5 is a perspective view of part of the side disk; and Fig. 6 is a sectional view of the 50 stationary pin and pitmen, showing the manner of lubricating the journals thereof.

Like letters of reference indicate like parts in each.

The engine shown is a compound engine having the live-steam cylinder A and the ex-

haust-steam cylinder B, the steam passing from 55 one cylinder to the other through ports or passages in the bed-plate C, on which the cylinders are supported, as hereinafter particularly described.

The construction of the cylinders is the 60 same, the exhaust-cylinder and parts contained therein being increased in width according to the necessary enlargement of the steam-space therein.

The cylinders A B are secured at opposite 65 ends of the bed-plate C, and the power-shaft D extends between the two cylinders, carrying the band wheel or pulley d, from which the rotary motion generated in the engine is transmitted. The cylinders are bolted to the 70 bed-plate at b and are formed of the cylinder-body a and the cylinder-heads a' a'', the head a' having the hub a³ extending out therefrom, within which is journaled the power-shaft D, the journals for said shaft being shown at d' 75 at the outer ends of the hubs a³. The shaft D carries at each end the rotary piston-head E, which is provided with a collar, f, extending within the enlargement a⁴ of the hub a³ and keyed to the shaft, as at f', the shafts not extending into the piston-head, for the reason 80 that the space therein is required for the operation of the pistons.

The piston-head E is provided with the side plates or disks, F F', which are rigidly attached 85 to the piston-head, and in the preferred construction the collar f is found as part of the disk F, and the disk is secured rigidly to the piston-head by bolts. These disks or plates F F' are of greater diameter than the steam- 90 space K of the cylinder, and extend into annular recesses K' therein, formed between the cylinder-body a and the cylinder-heads a' a'', the annular recesses K' and the side plates, F 95 F', being concentric with the power-shaft D. In order to pack the side plates within the annular recesses K' any suitable form of packing may be employed, the drawings showing the spring-actuated packing-rings in the cylinder-body a pressing against the inner faces 100 of the side plates close to the peripheral edges thereof.

The piston-head is hollow, to form space for the reception and operation of the stationary pin P, and the pistons G G', pitmen or arms H H', hereinafter described, and has the guide-slots e, in which the pistons slide. The piston-head is mounted on the power-shaft D, eccen-

trically to the steam-space K of the cylinder, the piston being in contact with the interior wall, k, thereof at the base of the steam-space, and, if desired, a spring or steam actuated 5 packing-plate, K⁴, at the base of the cylinder bears against the piston-head, steam being admitted between the plate K⁴, through holes K⁵, from the cored-out portion K⁶, which communicates with the steam-inlet L, as shown in 10 the drawings.

Ports l' m' m' communicate with the steam-space K through the interior walls, k, on each side of the point of contact with the piston-head—the ports l' m' near said point of contact, 15 and the ports l m at points just below a line drawn horizontally through the center of the cylinder-space K, the ports l' m' communicating with the ports l m. These ports communicate through the slide-valve N with the steam- 20 inlet L and the exhaust-passages M M', on each side thereof, in the bed-plate C, the steam entering at L, passing thence through the central opening, n, in the slide-valve into the port l, and through said port and the auxiliary port 25 l' into the steam-space K, and thence through the ports m' m' and around one end of the slide-valve into the exhaust-passage M, and on the reversal of the engine, by the movement of the slide-valve, the steam passing in 30 the opposite direction through the steam-space and exhausting from the ports l into the exhaust-passage M'. The valve N is operated by a lever, n', by means of the rod n², extending through the stuffing-box n³, its movement 35 being limited by the set-screw n⁴.

Extending in the interior of the piston-head E at the center of the interior space, K, of the cylinder is the stationary pin P, supported in the collar a⁵ on the cylinder-head a', 40 the side plate, F', having a central opening, f², to permit it to rotate around the collar a'. Journaled on said pin are the pitmen or arms H H', the pitman H having the single journal h, and the pitman H' having the two journals 45 h'; and journaled at the outer ends of the pitmen are the pistons G G', the pitmen having journals h², through which pins h⁴ pass. As the steam passing into the space K through the ports l' l' presses against the pistons it forces 50 them around the steam-space, imparting the rotary motion to the piston-head, and as the head rotates the pistons are projected out of the head and drawn into it by the pitmen journaled to the stationary pin P, the pitmen 55 turning on the pin and the pistons swinging slightly on the ends of the pitmen and being held in contact with the walls k of the cylinder by the pitmen, the movement of the pitmen and pistons being indicated by dotted 60 lines.

To accommodate for the necessary swinging of the pistons on the pitmen, on account of the different centers of the piston-head and the stationary pin, the steam-space K is slightly 65 higher than wide, and when the head is turned in the position shown in Fig. 3, as the guide-slots e extend radially from the center of the

head and the pistons are projected on that line, the pitmen conform to that line, though working from the pin P as a center, and hence 70 the distance from the pin p to the wall k at that point is less than at a line drawn through the centers of both the head and the pin P, where the pitmen and pistons are necessarily on the same line. As the steam presses against 75 the pistons where they project beyond the piston-head and thus causes the rotation of the engine, one or the other piston is always projected beyond the head and receives the pressure of the steam. The piston passes the lower 80 steam-port, l', before it is projected far beyond the head at the commencement of its stroke, and back-pressure upon it is thus prevented, and when a greater surface of piston is exposed steam is supplied through both 85 ports l' l', and in like manner the steam is first exhausted through both ports m' m', and the port m' receives the exhaust-steam until the piston is almost withdrawn at the end of its stroke. As the side plates, F F', rotate with 90 the piston-head and pistons, I form in their inner faces guiding-grooves r, in which the edges of the pistons move, the pistons being thus supported in their stroke by the side plates, as well as the piston-heads; and in 95 order to close the upper ends of these grooves and prevent the escape of steam through them between the cylinder body and plate, I form at the outer ends of the pistons the lips g', which extend a short distance beyond the 100 interior wall, k, of the cylinder, and as the pistons are held continuously in contact with the wall k, they thus prevent the escape of steam around them. In order to allow for 105 slight irregularity in the interior wall, k, of the cylinder, or in regular movement of the pitmen or pistons, I form spring-actuated packing-bars g² at the ends of the pistons, these bars pressing against the interior wall, k, continuously; and to form steam-tight joints between the pistons and the bases of the grooves r in the side plates in which they slide I provide spring-actuated packing-bars r' in the 110 side edges of the pistons, all the edges of the pistons exposed to the steam-pressure being 115 thus suitably packed.

In order to lubricate the journals h h' h² of the pitmen, I form in the stationary pin P the bore p, extending centrally from the outer end past the journals h h', and secure at the outer 120 end of the pin the oil-cup p', communicating therewith. Extending through the lower part of the pin P and communicating with the bore p are the oil-holes s s²—the oil-holes s in the center of the journal h and the oil-holes s' within 125 the journals h'—the oil-holes thus furnishing oil to lubricate these journals. It is necessary also to lubricate the journals h², and to accomplish this I form the oil-holes s², extending from the pin P through the body of the pitman H to the journal h² thereof, and I provide 130 the pitman H' with the web or body h³, fitting close to the journal h of the pitman H, and form through said journal h the oil-hole s³, and

opposite said hole the oil-hole s^4 , extending through the web h^3 to the journal h^2 of said pitman H' , the end of the hole s^4 , next the hole s^3 , being enlarged to catch any oil passing through the same and feed it to said journal h^2 .

In Fig. 2 is shown the bed-plate C , illustrating the manner in which the steam enters the cylinder A , and passes thence to the exhaust-cylinder B . The steam enters through the supply-pipe t into the central steam-inlet, L , in the bed-plate, and rising thence through the port c and the central opening, n , in the slide-valve N to the port l or m , according to the position of said valve. After passing through the cylinder A it passes through the port c' or c^2 into the exhaust-passage M or M' , at the side of the central steam-inlet, L . These passages M M' , after passing beyond the steam-inlet L , which is closed by an end wall, unite in the longitudinal passage M^2 , which extends within the bed-plate to the exhaust-cylinder B , and the steam enters through the central port, b^3 , and valve N into that cylinder, and after passing through the same passes through the port b' or b^2 into the exhaust-passage U or U' , on each side of the passage N^2 . The passages U U' then unite at the end of the bed-plate and communicate with the steam-outlet U^2 , to which the exhaust-pipe u is connected.

The slide-valves N in the two cylinders are connected by the rod N^2 , to which the lever N' is keyed, and which extends to the opposite end of the engine and operates the slide-valve therein.

When the engine is in operation, steam enters at the port t , passes into the steam-inlet L , thence through the ports l l' into the cylinder-space K , or the live-steam cylinder a , and pressing against the pistons G G imparts a rotary motion to the piston-head and through it to the power-shaft, and passes out through the ports m m' into the exhaust-passages M or M' in the bed-plate. It then passes through the longitudinal passage M^2 to the exhaust-steam cylinder B , and passes through the same course therein, the pressure of the expanded exhaust-steam being thus utilized to increase the power of the engine, and to cause the more even rotation of the shaft than where power is only applied at one side of the point from which the rotary motion generated is transmitted to the mechanism to be operated.

The engine is simple in construction, and as there are but few parts it is not liable to wear or get out of order. Practical operation has proved that a speed as high as fifteen hundred revolutions per minute can be obtained.

What I claim as my invention is—

1. In rotary engines, the combination, with the piston-head secured concentrically to the power-shaft and rotating within the steam-space eccentrically therein, of the stationary pin extending in the center of the steam-space and within the piston-head and being supported therein by a collar formed on the inner side of the cylinder-head, the pitmen journaled thereon, and the pistons pivoted to the

pitmen and sliding within the piston-head, substantially as and for the purposes set forth.

2. In rotary engines, the combination, with the cylinder, of the piston-head rotating within the steam-space thereof and having side plates or disks provided with guiding-grooves and the sliding pistons fitting into said grooves and having spring-actuated packing-bars on their side edges within said guiding-grooves, substantially as and for the purposes set forth.

3. In rotary engines, the combination, with the cylinder, of the hollow piston-head E , secured concentrically on the power-shaft and rotating eccentrically within the cylinder, the side plate, F' , thereof having the central opening, f^2 , and the stationary pin P , extending through said opening into the rotating piston-head, substantially as and for the purposes set forth.

4. In rotary engines, the combination of the cylinder having the hub a^3 extending out at one side thereof, the power-shaft D , journaled in said hub, the piston-head E , and the side plate or disk, F , rigidly secured to the piston-head and provided with the collar f , secured to the power-shaft within the hub a^3 , substantially as and for the purposes set forth.

5. In rotary engines, the combination of the stationary pin P , extending through the cylinder-head and having the central bore, p , and oiling-hole s , and the pitman H , mounted on the pin P , by means of the journal h , and having the journal h^2 , and provided with the oil-hole s^2 , extending from the journal h to the journal h^2 , substantially as and for the purposes as set forth.

6. In rotary engines, the combination, with the stationary pin P , extending through the cylinder-head and having the central bore, p , and oiling-hole s , of the pitmen H H' , mounted on said pin, said pitman H having the oil-hole s^3 in its journal h , and said pitman H' having the oil-hole s^4 opposite said oil-hole s^3 and extending to the journal h^2 of said pitman, substantially as and for the purposes set forth.

7. The bed-plates for compound rotary engines, having the supply-pipe t , central steam-inlet, L , and exhaust-passages M M' at the sides of the inlet L , said exhaust-passages M M' uniting in the longitudinal passage M^2 , leading through the bed-plate to the exhaust-steam inlet at the opposite end of the bed-plate, substantially as and for the purposes set forth.

8. In rotary engines, the combination of the bed-plate, the live-steam cylinder A at one end, the exhaust-steam cylinder B at the other end, and the power-shaft D , carrying rotary piston-heads in said cylinders and having the band-wheel secured thereto between said cylinders, substantially as and for the purposes set forth.

In testimony whereof I, the said JOHN BEYSTRUM, have hereunto set my hand.

JOHN BEYSTRUM.
